UNITED STATES PATENT OFFICE.

GEORGE F. ROYER, OF WILKES-BARRE, PENNSYLVANIA.

SAFETY ATTACHMENT FOR HOISTING MACHINERY.

1,129,733.

Specification of Letters Patent. Patented Feb. 23, 1915.

Application filed May 12, 1914. Serial No. 838,136.

To all whom it may concern:

Be it known that I, GEORGE F. ROYER, a citizen of the United States, resident of Wilkes-Barre, Luzerne county, State of Pennsylvania, have invented certain new and useful Improvements in Safety Attachments for Hoisting Machinery, of which the following is a specification.

The present invention relates to improvements in means for controlling, or safety attachments for, hoisting or elevating machinery and is particularly adapted for use in connection with mine hoists.

In the accompanying drawings: Figure 1 is a plan view of an embodiment of the invention; Fig. 2 is an elevation; Fig. 3 is a vertical sectional view; Fig. 4 is a sectional view through a portion of the brake actuating cylinder and its controlling valve mechanism; Figs. 5, 6, 7 and 8 are detail views.

While the invention is adapted for use with machinery operated by steam, electricity or any other suitable motive power, it will, for purposes of description, be considered as applied to mine hoisting machinery in which a steam engine is employed to actuate a winding drum or drums. As embodiments of the invention may manifestly be applied to or used in connection with any suitable engine, winding drum, cage, etc., such parts of a mine hoist are not illustrated.

In the drawings, A designates a shaft which is shown as mounted in suitable bearings on a pedestal-like support and has secured to one end a sprocket A' which is connected by a chain C with the engine drum shaft C', on which the winding drum is mounted or by which said drum is adapted to be driven.

At its opposite end the shaft A is provided with a bevel pinion a which meshes with a corresponding bevel a' at the lower end of a sleeve D mounted in a bearing on the supporting pedestal. A shaft E extends through the sleeve D to which it is connected by a suitable key permitting the shaft to be adjusted longitudinally of the sleeve while rotating therewith; and adjacent its upper end this shaft is engaged by the inner ends of the lever-like arms F of a centrifugal speed governor, the outer ends of said arms having mounted thereon spherical weights f.

To the lower end of the shaft E is secured a disk e which is provided adjacent its per-

iphery with a depending lug e'. As the speed of the engine shaft varies the shaft E will be moved vertically by the action of the weights f and means are provided whereby when an undesirably high, or dangerous, speed is attained or the winding cable has been wound to the desired extent on its drum, the lug e' will be caused to automatically effect operation of the brake mechanism provided for checking rotation of the winding drum or engine shaft.

A gear a² on the shaft A meshes with a gear g on a counter shaft G which shaft is geared to a worm g' that engages a worm gear H mounted on an arm projecting laterally from the pedestal B. The several parts are so proportioned that the worm wheel H will make less than a complete rotation during the maximum permissible length of travel of the cage or car of the hoisting machine to which the invention is applied.

The worm wheel H is preferably recessed on its upper face and said recess is partly covered by a plate I which is securely attached to the hub of the worm wheel so that it will always turn therewith. To the central stud or post about which the worm wheel turns is pivotally connected a lever arm K that extends radially of the wheel beyond the periphery thereof and into a socket or recess formed in the head L at the upper end of a sleeve L' which is shown as extending through the top plate of the supporting pedestal. The head L is provided with a laterally projecting arm L² which extends beneath the disk e at the lower end of the governor actuated shaft E and lies within the path of the lug e' on said disk when the latter has been shifted downward from its normal position a predetermined extent.

A valve actuating rod M is connected with the sleeve L' by a pin and slot permitting vertical movement of the sleeve independent of the rod but insuring that the rod and valve disk N at the lower end thereof will be caused to turn with the sleeve whenever the latter is actuated by engagement of the lug e' with the arm L² as above referred to. The valve disk N controls ports o in a diaphragm extending across an exhaust passage O, the section of which above the valve is provided with a branch or duct o' that is connected by a suitable pipe with an outlet p³ at one end of a valve casing P (shown in section in Fig. 4) the opposite end of

which is in communication with a brake actuating cylinder Q. The valve casing P is divided into two chambers by a piston P' having a pressure equalizing port p formed therein; and a spring P² coöperates with said piston and an end wall of the casing to act to retain the piston on its seat. To the opposite face of the piston from the spring P² is attached a slide valve P³ adapted to control communication between an inlet port p' and the brake actuating cylinder Q and between said cylinder and an exhaust port p². The inlet port p' of the valve casing P is in constant communication with the main pressure pipe of a fluid pressure brake mechanism; and when the engine is operating at normal or permissible rate of speed the disk N will close the ports o and, through the equalizing port p, the piston P' will be subjected to equal pressure on both faces and the parts within the valve casing occupy the positions shown in Fig. 4 in which the slide valve P³ cuts off communication between the inlet port p' and the cylinder Q, the latter being in communication with the exhaust port p². If, however, the speed of the engine increases beyond the desired limit the centrifugal governor will lower the shaft E so that the disk e thereon will be caused to turn the valve rod M and its attached disk valve N to open the ports o. This causes a reduction of pressure on the adjacent side of the piston P' so that the pressure of the main line, acting through the port p', will move the piston against the action of the spring P² and shift the slide valve P³ to admit pressure to the brake actuating cylinder Q and thus apply the brakes and check movement of the winding drum or engine shaft. When the ports o are again closed the pressure in the valve casing on both sides of the piston will be equalized and the spring P² will return the piston to its normal position shifting the slide valve P³ into the position shown in Fig. 4.

The invention also includes means by which, even if the speed of the engine shaft or winding drum during a hoisting operation does not exceed the desired limit, the brake mechanism will be automatically actuated if through oversight, or accident, the operative in charge fails to stop the hoisting operation when the cage has been raised to the landing level or permits the cage to approach the landing at an undesirably high speed. For this purpose the worm wheel H is provided with an upwardly projecting cam member adapted to coöperate with the lever K to raise the arm L² into the path of the lug e'. The cam member referred to comprises a plate R extending parallel to the periphery of the worm wheel and having at one side an arm r that extends beneath the plate I and is provided with a depend-

ing pin r' that extends into a suitable socket or opening in the base of gear H. On its outer face the plate R is provided with two inclined or cam surfaces R' and R² and with said surfaces are adapted to coöperate a finger s and a roller s' on an arm S that is secured to and depends from the lever K. The cam surface R' is relatively long and corresponds to the normal or proper movement of the worm wheel during each hoisting operation. That is, when the machinery is properly controlled the projection or finger s at the lower end of the arm S will travel over the cam surface R', but this will not lift the arm L² above the plane of the dotted line Y (Fig. 3) or into the path of the governor actuated lug e'. The two cam surfaces R', R² are separated by a gap or space of sufficient size to permit the finger s to pass therethrough so that as the cage or car reaches its landing said finger will have passed from the cam surface R' and being above said gap or space the lever K and arm L² will fall to their normal position.

To prevent the arm S from interfering with the return movement of the worm H and the cam plate R, the cam surface R' is preferably formed on a member which is pivotally connected as at T² to the plate R and during the return movement of the worm wheel said cam member will be rocked about its pivot to permit the finger s to pass beneath the same and into position to ride over the upper surface of a face of said cam on the next operative movement of the cam wheel. If through oversight or accident the operator does not stop the movement of the machinery when the worm wheel has been turned so that the space or gap referred to is in alinement with the finger s, and the lever K and arm S can fall to their normal positions, as above described, the second cam surface R² will coöperate with the roller s' and impart sufficient additional lifting movement to the arm L² as to bring it into the path of the governor actuated lug e' and consequently effect actuation of the brake mechanism, as previously described. As thus described, the apparatus is complete if but a single winding drum is employed. It is, however, customary in mine hoists to employ at least two winding drums so related that the cage or car attached to one will be ascending while the other is descending by which arrangement one cage may be loaded while the other is unloaded. In such constructions it is common to connect one of the winding drums rigidly with the power shaft while the other is connected therewith by a suitable clutch permitting it to be disconnected at will. To adapt the present invention for use with such a hoisting mechanism, the worm wheel H is provided with a second cam member T similar to that before described but ar-

ranged in such relation thereto that it will coöperate with the lever K during movement of the wheel in the direction which carries the cam member R away from its operative position. As shown, the periphery of the plate I, or a sufficient portion thereof, is provided with teeth i and the arm of said cam plate T is provided with a tooth or teeth i' . A leaf spring, as r^3 , connected 5 with the arm t of the cam plate, for instance to the depending pin t' and coöperating with abutments on the lower face of the plate I, may be employed to hold the cam plate securely in the desired engagement 10 with the teeth i and proper position on the worm gear H.

It is necessary that the cam member T be disconnected from the worm wheel when the clutch connecting the corresponding 15 winding drum with the power shaft has moved to release said drum. To effect this, a bell crank U, fulcrumed on a depending lug on the top plate of the supporting pedestal, has its upper arm provided with a 20 notch adapted to receive the depending pin of the cam plate T. The other arm of said bell crank U is connected with the lever or other device (not shown) for actuating the clutch, by which connection of the aforesaid winding drum with the power shaft is 25 controlled. It will be seen that when the bell crank U is rocked by the action of unclutching said drum from the power shaft, the cam plate T will be moved bodily 30 radially of the worm wheel H sufficiently to disengage it from the plate I and will be held stationary by the bell crank which, as shown, has a recess or notch that receives the pin t' . While the winding drum provided with the clutch referred to and the cam plate T are thus held stationary, the cage or car connected with said drum being at 35 this time in alinement with a landing, the drum that is permanently connected with the power shaft will be actuated to raise or lower the cage connected therewith until it is opposite the desired landing. The proper distance between and relation of 40 the two cages being thus established, the second drum will be again clutched to the power shaft, this action releasing the cam plate T and permitting the spring coöperating therewith to effect reengagement of said cam with the toothed periphery of the plate I. Thereafter, as will be evident, the lever K will be actuated to effect operation of the 45 brake mechanism if the worm wheel H is moved beyond the proper limits in either direction, regardless of the speed at which the engine shaft or winding drums are moving.

To assist the operator in controlling the machinery, a signal, adapted to be automatically operated from the mechanism hereinbefore described, is provided. This 50

comprises a lever V fulcrumed on a stud or post e^2 rising from the head L, at the upper end of the sleeve L'. This lever is of such length that one end thereof projects beneath a flange on the disk e. The other end thereof is connected by a link with a signal plate W which is pivotally mounted on a projection from the post or stud about which the worm gear H turns. As the governor actuated shaft is forced downward the lever 55 V will be rocked about its fulcrum and the signal plate W rocked about its pivot. When the disk e has been depressed so that its lug e' is operating in the plane indicated by the line Y, Fig. 3., which is the position assumed when the winding drums or engine shaft are rotating at normal speed, the plate W will occupy the position indicated by dotted lines at W'. Should the speed of the drums or shaft be increased further downward movement of the disk e would cause the plate W to assume the position indicated in the dotted lines at W² even before the valve disk N is actuated to set the brake operating devices in operation. The same result, that is shifting of the signal plate from the dotted line position W' to the dotted line position W², will occur if the operator fails to stop the winding devices when the upper cage has reached the desired limit of its movement and the sleeve L' is raised by action of the cam plates R or T, as previously described.

From the foregoing description of the drawings, it will be seen that the invention 100 provides a very simple and positively acting means for controlling elevating machinery and by which the power shaft will be stopped when the speed thereof exceeds a predetermined limit or if the operator does 105 not properly reduce the speed as a car approaches a landing.

While the invention is described as including fluid pressure brake mechanism, it 110 will be evident that the fluid pressure devices might be adapted for actuating other controlling means than brakes, for instance to reverse the engine.

Having thus described the invention, what is claimed and desired to be secured by 115 Letters Patent is:

1. In apparatus of the character described, the combination of a power shaft, fluid pressure mechanism controlling movement of said shaft, a valve controlling operation of the fluid pressure mechanism, an actuating device for said valve connected with the shaft and movable to and from operative relation to the valve as the speed of the shaft varies, a member connected with the valve and adapted to be engaged by said actuating device if the speed of the shaft exceeds a predetermined limit at any time, and means for adjusting said member relative to the valve and actuating device to 125

effect movement of the valve when the shaft has completed a predetermined number of revolutions.

2. In apparatus of the character described, the combination of a power shaft, fluid pressure mechanism controlling movement of said shaft, a valve controlling operation of the fluid pressure mechanism, an arm adjustably connected with the valve, a rotary actuating device connected with the shaft and movable to and from a position where it will engage said arm as the speed of the shaft varies, and means geared to the shaft and adapted to adjust said arm relative to the rotary actuating device, for the purpose described.

3. In apparatus of the character described, the combination of a power shaft, fluid pressure brake mechanism, a control valve for the brake mechanism having a longitudinally extensible stem, a centrifugal governor connected to the shaft, a rotary contact member connected to the governor to be shifted thereby to and from a position where it will engage said valve stem and actuate the valve to render the brake mechanism operative, and means connected with the shaft for varying the length of the valve stem, for the purpose described.

4. In apparatus of the character described, the combination of a power shaft, fluid pressure mechanism controlling movement of said shaft, a valve controlling operation of the fluid pressure mechanism, an arm connected with the valve, a rotary contact member movable as the speed of the shaft varies to and from a position where it will engage said arm, whereby the valve will be automatically shifted to render the fluid pressure mechanism operative when the speed of the shaft exceeds a predetermined limit, a gear connected with the shaft, and means moving with the gear adapted to move said valve arm toward the path of said rotary contact member, independent of the speed at which the shaft rotates.

5. In apparatus of the character described, the combination of a power shaft, fluid pressure mechanism controlling movement of said shaft, a valve controlling operation of the fluid pressure mechanism, an arm secured to the valve stem by means permitting it to move longitudinally thereof, a rotary contact member movable as the speed of the shaft varies to and from a position where it will engage said arm, whereby the valve will be automatically shifted to render the fluid pressure mechanism operative when the speed of the shaft exceeds a predetermined limit, a lever connected with the arm on the valve stem, and means geared to the power shaft and adapted to move said arm toward the path of said rotary contact member independent of the speed at which the shaft rotates.

6. In an apparatus for controlling elevating machinery, the combination with a power shaft and a centrifugal governor connected with said shaft, of a disk adapted to rotate about the axis of the governor shaft and to move longitudinally thereof, a fluid pressure brake mechanism for the power shaft, a valve adapted to be positioned to effect actuating of the brake mechanism, and means connected with said valve and extending into position to be engaged by said disk when the speed of the power shaft exceeds a predetermined limit.

7. In an apparatus for controlling elevating machinery, the combination with a power shaft, of a fluid pressure brake mechanism including a rotary control valve, a speed governor connected with the shaft and including a rotary member adapted to be adjusted longitudinally of its axis as the speed of the shaft varies, and an arm connected with said rotary valve and extending into the path of said rotary member when the speed of the shaft exceeds a predetermined limit.

8. In an apparatus for controlling elevating machinery, the combination of a power shaft, fluid pressure mechanism controlling movement of said shaft, a valve controlling operation of the fluid pressure mechanism, an actuating device for said valve connected with the shaft and movable to and from operative relation to the valve as the speed of the shaft varies, whereby the valve will be automatically actuated when the speed of the shaft exceeds a predetermined limit, and a signal device for indicating the relative speed of the shaft at all times.

9. In an apparatus for controlling elevating machinery, the combination of a power shaft, a rotary member connected with the shaft and adjustable in the direction of the length of its axis as the speed of the shaft varies, a fluid pressure mechanism controlling movement of the shaft, a valve for said mechanism adapted to be actuated by said rotary member when the speed of the shaft exceeds a predetermined limit, and a signal device adapted to be operated by movement of said rotary member in the direction of the length of its axis, for the purpose described.

10. In an apparatus for controlling elevating machinery, the combination of a power shaft, fluid pressure mechanism controlling movement of said shaft, a valve controlling operation of the fluid pressure mechanism, an actuating device for said valve connected with the shaft and movable to and from operative relation to the valve as the speed of the shaft varies, a gear rotatable by the shaft, and means on said gear for causing said actuating device to operate the valve independent of the speed at which the power shaft rotates when the said

- shaft has completed a predetermined number of revolutions in either direction.
11. In an apparatus for controlling elevating machinery, the combination of a power shaft, fluid pressure mechanism controlling movement of said shaft, a valve controlling operation of the fluid pressure mechanism and provided with a longitudinally extensible stem having at its free end 10 a lateral projection, a contact device rotatable by the shaft and movable to and from a position to engage the valve stem as the speed of the shaft varies, a gear rotatable by the shaft, and cam surfaces on said gear 15 adapted to vary the length of the valve stem to bring the projection thereon into the path of said actuating device, when the shaft has completed a predetermined number of revolutions in either direction.
12. In an apparatus for controlling elevating machinery, the combination of a power shaft, fluid pressure mechanism controlling movement of said shaft, a valve controlling said fluid pressure mechanism 20 and provided with a projecting arm, a rotary contact device geared to the power shaft and movable to and from position where it will engage said valve arm as the speed of the shaft varies, a lever engaging 25 said valve arm and adapted to adjust the same toward the path of the rotary contact device, a gear connected with the shaft, and means on said gear for coöperating with the lever to adjust said valve arm into the 30 path of the rotary actuating device on the completion of a predetermined number of revolutions of the shaft in either direction.
13. In an apparatus for controlling elevating machinery, the combination of a power shaft, fluid pressure mechanism controlling movement of said shaft, a valve controlling operation of said fluid pressure mechanism, a rotary actuating device connected with the shaft and adjustable to and 40 from the position where it can operate said valve as the speed of the shaft varies, and a gear connected with the shaft and provided with a cam adapted to cause said actuating device to operate the valve independent of 45 the speed of the shaft when the shaft has completed a predetermined number of revolutions.
14. In an apparatus for controlling elevating machinery, the combination of a power shaft, a fluid pressure mechanism controlling operation of the shaft, a valve controlling the fluid pressure mechanism and having an extensible stem terminating in a lateral arm, a rotary actuating device 50 geared to the shaft and adjustable to and from said arm on the valve stem as the speed of the shaft varies, a lever engaging the valve stem, a gear connected with the power shaft and provided with a plurality 55 of cam surfaces adapted to coöperate with said lever to adjust the arm on the valve stem into the path of said rotary actuating device on the completion of a predetermined number of revolutions of the shaft in either direction, and means for disconnecting one 60 of said cams from the gear at will.
15. In apparatus of the character described, the combination of a power shaft, fluid pressure mechanism controlling movement of said shaft, a valve controlling operation of the fluid pressure mechanism, two relatively movable members connected respectively with the valve and power shaft and adapted to be related so that the valve will be actuated by the shaft, a lever adapt- 75 ed to effect relative movement of said members, and a cam rotatable by the shaft and having two separated surfaces adapted to successively act on said lever if a pre- 80 determined number of revolutions of the shaft 85 is exceeded, the second of said surfaces moving the lever sufficiently to bring the valve actuating members into operative relation.
16. In apparatus of the character described, the combination of a power shaft, 90 fluid pressure mechanism controlling movement of said shaft, a valve controlling operation of the fluid pressure mechanism, two relatively movable members connected respectively with the valve and power shaft 95 and adapted to be related so that the valve will be actuated by the shaft, a gear rotatable by the power shaft and provided with two circumferentially separated cam surfaces, and a lever adapted to effect relative 100 movement of the valve actuating members extending into the paths of said cams, the parts being so positioned that the lever is engaged by only one of said cams if the power shaft is stopped on the completion of 105 a predetermined number of revolutions and is engaged by the other cam if such pre- 110 determined number of revolutions of the power shaft is exceeded.
17. In apparatus of the character described, the combination of a power shaft, fluid pressure mechanism controlling movement of said shaft, a valve controlling operation of the fluid pressure mechanism, means for operating the valve including two 115 relatively movable members one of which is rotated by the power shaft, a lever adapt- 120 ed to shift one of the said valve operating members, a cam rotated by the power shaft and adapted to coöperate with said lever to effect actuation of the valve if the shaft rotates in one direction beyond a predetermined limit, and a second cam adjustable toward or from the first and adapted to similarly operate the lever on the completion of 125 a predetermined number of revolutions of the shaft in the opposite direction.
18. In apparatus of the character described, the combination of a power shaft, fluid pressure mechanism controlling move- 130

ment of said shaft, a valve controlling operation of the fluid pressure mechanism, means for operating the valve including two relatively movable members one of which is 5 rotated by the power shaft, a lever adapted to shift one of the said valve operating members, a gear rotated by the power shaft, two cam members R, T on said gear adapted to alternately coöperate with said lever to bring the valve operating members into operative relation as the shaft completes a pre-determined number of revolutions in opposite directions, each of said cams including 10

a pivotally mounted member R' with which the lever coöperates in the normal operation 15 of the mechanism, and a member R² separated from the member R' and coöperating with the lever when rotation of the shaft is not properly stopped.

In testimony whereof I affix my signature in presence of two witnesses.
